UNITED STATES PATENT OFFICE

2,036,333

METHOD OF AND APPARATUS FOR
FORMING GLASSWARE

George E. Howard, Butler, Pa., assignor to Hartford-Empire Company, Hartford, Conn., a corporation of Delaware

Application March 21, 1934, Serial No. 716,634

22 Claims. (Cl. 49—9)

This invention relates to a method of and apparatus for forming hollow glass articles, particularly bottles. More particularly the present invention relates to a method and apparatus of forming hollow glass articles wherein charges of glass are first formed into blanks or parisons in blank molds mounted upon a rotatable carrier, the blanks or parisons are then transferred by suitable transfer means to blow molds and are then blown to final form, and in which the transfer means is of such character that the blanks or parisons may be supported out of contact and out of registry with any body mold surface for a material length of time during which the reheating and gravity elongation of the blanks or parisons is permitted.

Recent studies in the making of glassware have resulted in a better appreciation than was had therefore of the importance of providing a relatively long reheating time between the times of contact of the glass with a blank or parison mold on the one hand and with a finish blow mold on the other hand. In most of the prior art commercial machines, this reheating operation was done to a great extent at least while the blank or parison was at the position of either the blank or blow molds, the blank mold while the parison was reheating in that position being partially and wholly open, and the blow mold while the parison was reheating in the blow mold position being either opened or closed. Should reheating be permitted for a material proportion of the total time used for making the articles, the blank and/or blow molds cou'd not be utilized for actual forming operations while this reheating was going on therein and hence a material amount of the total mold time would be lost for actual forming operations.

My present invention provides means whereby the major part of the reheating takes place while the blank or parison is out of contact and out of registry with either the blank or blow molds, so that these molds may be used a greater proportion of the entire time for actual forming operations, this being done to a major extent by what may be termed an overlapping cycle, that is, a cycle of operation of the machine in which several charges of glass are being formed simultaneously for each mold unit (a blank mold and a blow mold) of the machine. For example, it is possible to utilize the blank molds for a very large percentage of their time in actual forming operations while supporting parisons formed in these blank molds for reheating at some other position, or positions, (either moving or station-

ary) and at the same time employ the blow molds for a major proportion of their time in the actual blowing of reheated parisons to final form, thus separating the three steps of the process of making bottles, i. e., the blank forming, reheating and final blowing, and causing them to occur at different positions or zones in the path of the glass through the entire machine, the reheating positions or zone being to a large extent different from the paths of either the blank or blow molds.

Certain of the broader principles described hereinabove are disclosed and claimed in the co-pending application of Wadman, Serial No. 707,060, filed Jan. 18, 1934, and consequently are not claimed herein. My present invention deals with certain phases of the above discussed subject matter which are not disclosed by Wadman.

Among the objects of my present invention are to provide a method and an apparatus embodying a rotary type glass forming machine wherein provision is made for separating the reheating step of the glass forming process intermediate the blank forming and final blowing of the glass from the strictly forming operations on the glass and preferably also to provide for the controlling of the elongation of the parison during such reheating step.

A further object of the present invention is to provide elongation controlling means during the reheating, specifically suitable bottom supports by which the elongation of the parisons during reheating may be limited.

A further object of the present invention is to provide tong transfer means for moving parisons from invertible blank molds on one rotary carrier to blow molds on another rotary carrier, in which parisons may be moved to a level different from that of the blank molds so that the blank molds may be reverted and in readiness for receiving the next charge of glass at the next dwell station subsequent to the transfer station.

A further object of the present invention is to provide apparatus of the character above set forth, and also a method of operating that apparatus or other types of apparatus, by which several charges of glass may be simultaneously in the process of formation into completed articles for each blank mold used, thus utilizing the molds in a most efficient manner by performing such operations, as do not require the use of molds, out of contact and out of registry with the molds.

A further object of the present invention is to provide a method and apparatus particularly for use in conjunction with the methods and appa-

ratus hereinabove referred to in which parisons are formed having some portion larger in at least one transverse direction than the corresponding portion of the article to be made and to permit the elongation and attenuation of the parisons so formed prior to enclosing them within the final blow molds, thus compensating by the form given to the blank or parison for the attenuation due to the running or elongation of the parisons under the influence of gravity during the reheating step of the process.

Further and more specific objects of my present invention will become apparent from the following specification and appended claims when taken in connection with the accompanying drawings, in which:

Figure 1 is a view principally in plan and partially in section on the line 1—1 of Fig. 2 showing a machine embodying my invention;

Fig. 1a is a fragmentary view principally in vertical section on the line 1a—1a of Fig. 1, looking in the direction of the arrows;

Fig. 2 is a view substantially in vertical section on the broken line 2—2 of Fig. 1, looking in the direction of the arrows;

Fig. 3 is a view substantially in vertical section on the broken line 3—3 of Fig. 1, looking in the direction of the arrows;

Fig. 4 is a fragmentary view principally in plan and partially in horizontal section showing certain details of the blank mold opening and closing means;

Fig. 5 is a view in plan of the top portion of the machine above the line 1—1 of Fig. 2;

Fig. 6 is a detail view in horizontal section on the line 6—6 of Fig. 2;

Fig. 7 is a detail view in vertical section on the line 7—7 of Fig. 5;

Fig. 8 is a fragmentary view, similar to the center portion of Fig. 2, but showing a modified form of the invention;

Fig. 9 is a diagrammatic plan view of the form of the device shown in Fig. 1;

Fig. 10 is a diagrammatic plan view similar to Fig. 9, but showing a modified form of the invention;

Figs. 11 to 17 inclusive are a series of diagrammatic views substantially in vertical section showing the various steps in the formation of a completed article and illustrating particularly the comparative size of the blank with respect to the completed article and the development of that blank;

Fig. 18 is a diagrammatic view illustrating in full lines the contour of the upper portion of a final blow mold and having superimposed thereon in dotted lines for purposes of comparison, the interior and exterior contour of a cooperating blank mold;

Fig. 19 is a fragmentary view principally in vertical section showing a modified form of bottom plate or parison elongation retarding device for use during the unconfined reheating of the parisons in the tongs; and

Fig. 20 is a development in elevation of a portion of the cams usable with the bottom plate structure of Fig. 19 showing also in vertical section a means for moving a sector of one of the cams vertically.

While I contemplate that my method may be carried out by machines of various types and also that from a broad point of view, apparatus may be built according to my present invention involving either an intermittent or continuous type of machine, I have chosen to illustrate the in-

vention in the accompanying drawings as an intermittent machine, that form shown in Figs. 1 to 7 for example including two laterally spaced rotary tables or mold carriers, one having four blank molds thereon and the other four blow molds thereon and there being a third rotary carrier having, as shown in Figs. 1 and 9, three tongs thereon. The Fig. 10 form of the invention is or may be the same as that shown in Figs. 1 and 9 with the exception that the tongs carrier is provided with four equally spaced tongs instead of three.

The frame of the machine

Referring first to Figs. 1 to 7 inclusive, I have illustrated a machine including a main base member 1, which may be mounted either upon the floor of a plant in which the machine is to be used or upon suitable wheels (not shown), as is customary with many glass forming machines now in use in the commercial art. Suitably secured to the base 1 is a supplementary base member 2 carrying the driving means and the timer for the machine. Suitably secured to the bottom of the base member 1 are annular bracket members 3 and 4 in which are fixed stationary vertical columns 5 and 6, as by pins 7 (Fig. 2), these columns serving as centers for the blank mold carrier 8 and the blow mold carrier 9 respectively, the carriers being supported upon suitable ball bearings as indicated at 10. At their upper ends, the columns 5 and 6 are tied together by a suitable structural member or casting 11, as shown in Figs. 2 and 5. Also mounted on the bottom web portion of the base 1 is a bearing member 12 receiving the lower end of the shaft 13, which in this case is rotatable and which carries the tongs as will be hereinafter described, the upper end of the shaft 13 being suitably journaled as at 14 in the member 11.

Rotating means for the mold carriers and tongs

I have shown for the purpose of the present application, means for rotating the mold carriers 8 and 9 and also the tongs carrier intermittently, although it is contemplated that certain of the broader phases of my invention at least may be applied to continuously rotating machines. For rotating the several carriers, there is provided a suitable source of power or prime mover, as the electric motor 15, the shaft of which is provided as illustrated (Fig. 1) with a sprocket wheel 16 connected to the sprocket wheel 17 of the speed changing device 18 by a suitable sprocket chain or other flexible driving means as diagrammatically illustrated at 19. The speed changing device 18 may be of any suitable or desired type and is preferably adjustable. For this purpose I may employ the device commercially known as the "Reeves" drive although it will be understood that any other suitable device effective to accomplish the purposes herein described may be employed in this connection. The device 18 is arranged to drive the sprocket wheel 20 which is connected to drive the sprocket wheel 21 by a suitable flexible endless driving means, as a sprocket chain diagrammatically illustrated at 22. The sprocket wheel 21 is secured to the shaft 23, the inner end of which carries the bevel pinion 24, best illustrated in Fig. 3. The bevel pinion 24 meshes with a bevel gear 25 which is freely rotatable upon a fixed shaft 26 secured to the bottom member of the base 1 supported also in the cover member 27 of the base 1, this cover member being used to prevent the ingress of dirt 75

or other foreign material into the driving gears. The bevel gear 25 is secured to an annular member 28 which carries a roller 29 (Figs. 1 and 2), thus forming the continuously rotating part of a Geneva movement mechanism. The roller 29 is adapted successively to enter the several slots 30 of a Geneva or star wheel 31, which is mounted for free rotation about a fixed shaft 32 suitably secured to the base member 1. The Geneva wheel 31 has secured thereto a large gear wheel 33 which meshes with a somewhat smaller gear 34 secured to the shaft 13 (Figs. 1 and 2). The gear 34 has secured thereto a larger gear 35 which meshes with the gear 36 secured to the blank mold carrier 8 and with gear 37 secured to the blow mold carrier 9. Thus intermittent motion imparted by the Geneva movement device to the star wheel 31 will be transmitted through the gears described to rotate the blank mold carrier 8, the blow mold carrier 9, and the tongs carrying shaft 13 intermittently and in the directions of the several arrows seen on Fig. 1.

It is also contemplated that means (not shown) be provided for imparting driving movement from the motor 15 and preferably from the shaft 23 to drive a suitable glass feeding device (not shown) for supplying charges of glass to the machine of my present invention in the well-known manner. Inasmuch, however, as such means are well known in the art, it is thought unnecessary to illustrate them in this instance.

The gearing just described, the major portion of which is contained within the confines of the bottom and sidewalls of the base member 1, is preferably enclosed to prevent the ingress of dirt, as hereinabove referred to, by cover members as illustrated at 27 and 38, these cover members being split so as to facilitate the construction of the machine substantially along the line 2-2 of Fig. 1 on which the section shown in Fig. 2 is taken, so that the cover member 27 appears in that figure in full lines rather than in section.

The timer

Inasmuch as many of the operating instrumentalities used in connection with the machine and hereinafter to be described are pneumatically operated, I have illustrated for controlling the timing of these various instrumentalities a timing device generally indicated at T, which device may be of the same or similar form to that now in use in the commercial "Hartford I. S." machine, this device being illustrated and described in the Ingle Patents 1,843,159 granted Feb. 2, 1932 and 1,911,119, granted May 23, 1933.

Briefly the device comprises a rotating drum 39 having a plurality of undercut circumferential slots thereon in any of which one or more buttons as shown at 40 may be adjustably secured. The valves 41 associated with the timer are arranged so that one valve will be opposite each of the slots in the drum. There is provided valve operating mechanism associated with each valve and arranged in alignment with each of the slots, these mechanisms being so constructed and arranged that when engaged by a short button, they will move their associated valves to a position to admit pressure from the main supply line 42 to the individual pressure lines to given operating mechanisms. When the valve operating mechanisms are thereafter engaged by longer buttons in the same grooves as the short buttons just referred to, the associated valves will be moved to positions to cut off the further supplying of pressure to the operating mechanisms con-

nected thereto and to exhaust such pressure to the atmosphere through the valves. The short and long buttons may be positioned at any desired point around the slots and locked in any adjusted position so that any of the pneumatically operated mechanism to be described may be adjusted to operate at the desired time or times in the cycle of operation of the machine.

The drum 39 is adapted to be driven from the shaft 23. As shown, the shaft 23 is provided with a pinion 43 secured thereto which is continuously in mesh with a large gear 44. The drum 39 may be clutched to the gear 44 by a clutch device, not illustrated herein, but fully illustrated and described in the Ingle Patent 1,911,119 above referred to, this clutch being operated pneumatically by the hand lever 45 shown in Figs. 1 and 3. The clutch operated by the hand lever 45 is of the single tooth variety so that the drum is always driven in a predetermined relation to the position of the parts of the forming machine and is driven one revolution for each intermittent step of rotation of that machine. The parts are therefore always operated in proper synchronized time relation to each other and at the same time any of the pneumatically operated means may be adjustably arranged to operate at any desired time in the cycle and for any desired period by suitably positioning the short and long buttons 40 on the drum 39.

Blank molds and mounting therefor

In the machine shown in Figs. 1 to 7 inclusive, there are four blank molds arranged equidistant about the blank mold carrier 8. The blank molds are of the invertible type and thus are usable for making "narrow neck" ware. Each blank mold is formed of complementary halves 46, as best seen in Fig. 4, the halves being suitably supported in the mold holders 47. The holders are pivoted upon a common pintle 48, this pintle being suitably secured in an invertible head 49. The head 49 is arranged for inversion about an axis radial of the blank mold carrier 8 and for this purpose is provided with a pair of inclined roller bearings 45 50 positioned at points spaced radially of the carrier. This provides both for the inverting movement of the head and also against thrust and movement in a direction radially of the carrier.

Blank mold inverting means

Means are provided for inverting the blank molds when desired and for preventing such inversion when it is desired that the blank molds be held in either inverted or reverted positions. In the present instance, such means comprises a bevel gear 51 rigid with the head 49 for each blank mold and positioned between the bearings 53 thereof. These gears are adapted to engage a stationary rack member 52, as seen in Figs. 1 and 2, this construction being similar to that employed in many of the commercial Lynch machines of the older type.

The various stations for the blank molds on the machine are lettered A, B, C and D respectively, station A being the charging station as seen in Figs. 1 and 9 and station C the transfer station. The inversion of the blank molds takes place between stations D and A to move the blank molds from a neck-up position at station D to a neck-down position at station A. The rack member 52 is continued from station A almost to station B, so that in moving from station A to station B, the molds are again brought to a neck-up position.

Thus while the molds are at station A they are

maintained against rotation about the radial axis of their heads 49 by the engagement of their gears 51 with the rack 52. During the movement of the molds from station B through station C to station D, it is desired that rotation thereof about their radial horizontal axes be prevented. For this purpose a portion of the hub of the mold carrying head 49 radially inward of the gear 51 is flattened at least on one side and is arranged for movement in sliding relation with a stationary sector 53, thus preventing inversion of the blank molds during this movement. This sector 53 is suitably cut away opposite the rack portion 52 between stations D, A and B. This construction is best illustrated in Figs. 2, 3 and 4. The rack member 52 and the sector member 53 are or may be integral as shown and are preferably secured as by the set screw 54 (Fig. 2) to the stationary column 5.

20 *The neck rings*

Each of the blank molds 46 of the machine being described has associated therewith a neck ring 55, which is preferably formed in complementary halves, the halves being interchangeably received in suitable holders 56 pivoted coaxially with the holders 41 for the blank molds on the pintle 48, but arranged for independent movement with respect to the blank molds, at least as to the opening of the neck rings.

30 *Opening and closing means for the blank molds and neck rings*

Inasmuch as the machine illustrated in Figs. 1 to 7 of the accompanying drawings is of the intermittent variety, it is unnecessary that the opening and closing means for the blank molds and neck rings move with the blank mold carrier. It is highly desirable if not essential, however, that there be some means other than friction for retaining the blank molds and neck rings against either opening or closing movement, as the case may be, while out of control of the non-rotating opening and closing means used therewith. In order, therefore, to minimize the mechanism which must be rotated, I preferably provide non-rotating blank mold opening and closing means, and also provide means moving with the molds for preventing their being opened or closed inadvertently during such movement.

50 Considering first the blank molds and referring to Fig. 4, the mold holders 41 are connected by links 57 to the outer ends of cranks 58 pivoted on parallel pintles 59 in the head 49. The cranks 58 and pintles 59 have rigid therewith arms 60 carrying rollers 61. Suitable tension springs 62 are connected between studs secured in the arms 60, so that the tension of the springs 62 will be exerted on opposite sides of the centers of pintles 59 for the arms 60 and 58 when the blank molds are opened and closed respectively, as will be seen from a comparison of the position of these parts at the right and at the lower portion of Fig. 4. Thus the blank molds will be maintained resiliently either in their opened or closed position, due to the tension of the springs 62 and the over-center-throw arrangement just described.

70 The blank molds are preferably arranged to interlock the neck rings, as best illustrated in Figs. 11, 12 and 13, so that the blank molds may be opened while the neck rings remain closed, as will be seen from a comparison of Figs. 12 and 13, but at the same time closing of the blank molds

will serve to close the neck rings due to their interlocking arrangement.

At station C, which is the transfer station for the parisons from the blank molds into the tongs, it is desired first to open the blank molds so that 5 the parison may be supported solely from the neck rings, then to engage the tongs around the neck or finish portions of the articles beneath the neck rings, as particularly illustrated in Fig. 13, and thereafter to open the neck rings. 10

Means are provided for accomplishing these several operations. In the first place, there is provided means for opening the blank molds at station C. Such means comprises a pneumatic cylinder 63 (Figs. 1, 2 and 4), this cylinder being 15 mounted upon a suitable bracket which may in turn be secured to the cover plates 27 and 38. The piston rod of this cylinder carries a head 64, which is provided with a pair of beveled portions 65 for engaging the rolls 61. Thus when the 20 piston in the cylinder 63 is moved from its right hand to its left hand position as seen in Figs. 2 and 4, the rolls 61 will be moved substantially radially inward of the blank mold carrier, rotating their associated cranks 60 and 58 and opening 25 the blank molds 46.

The angle of the roll-engaging portions 65 of the head 64 is such that the piston within the cylinder 63 need not be retracted before the next 30 rotative movement of the blank mold carrier, the portions 65 having roll-engaging surfaces substantially concentric with the blank mold carrier at the open position of the blank molds, that is, at the left-hand position of the portions 65 as seen in Figs. 2 and 4. 35

The concentric character of the members 65 thus provides for positively holding the blank mold open while at station C and while moving away from this station rather than depending upon any non-positive means for this purpose. 40

The head 64 is provided with one or more rods 66 rigid therewith and slidably in suitable guide openings in the bracket supporting the cylinder 63, so that the head 64 will always be moved in a rectilinear path and rotation about the axis of 45 the piston rod will be prevented.

Pressure may be supplied to the right-hand end of the cylinder 63, as seen in Fig. 4, through the pipe 67 from the timer T, in a manner not shown, but which will be understood. Retraction of the piston within the cylinder 65 and movement of the head 64 to the right as seen in Figs. 2 and 4 may be accomplished either by pressure from the timer to the other end of cylinder 63 or as shown by the use of tension springs 68 55 extending between suitable anchorages on the cylinder 63 and studs on the head 64.

The neck rings are each provided with a resilient over-center-throw arrangement for retaining them either open or closed similar to that described for the blank molds, with the exception that the linkage is all substantially integral with the neck ring carriers or holders 56. These holders are arranged in scissors form and have their ends connected by tension springs 69 (Fig. 65 1), which extend between studs on the portions of the holders on the opposite side of the pintle 48 from that which carries the neck ring halves. These springs are moved, due to the opening of the neck rings, between positions on opposite sides of the pintle 48, as will be seen by a comparison of the position of the parts at stations C and D in Fig. 1.

The inwardly extending portions of the neck ring holders also have upturned ends as illus- 70 75

trated at 70 in Fig. 3 so that when a mold and neck ring come to rest at station C (the transfer station), these upwardly extending portions 70 are in radial alignment with a head 71 carried at the outer end of the piston rod of a pneumatic cylinder 72 which may be secured to the stationary column 5. Thus upon movement of the head 71 to the right as seen in Figs. 1 and 2, it will engage the upwardly extending portions 70 of the neck ring holders 56 and result in the opening of the neck ring. Pressure may be supplied to the cylinder 72 through the pipe 73 (Fig. 2) from the timer T for opening the neck rings at the desired time in the machine cycle. The head 71 is similarly provided with one or more guide rods 74 for preventing rotation of this head about the axis of the piston rod of cylinder 72 and with retracting tension springs 75 for returning the piston to its left hand position (as seen in Fig. 2) at the desired time, this time being controllable by the exhausting of pressure through the line 73 by the timer T.

The operation of the cylinder 72 in opening the neck rings is thus substantially the same as that of the cylinder 63 for opening the blank molds. Here again the configuration of the pusher member 71 is such as to permit the rotation of the blank mold carrier prior to the retraction of the head 71 so as to hold the neck rings open prior to the movements of the molds from station C toward the station D.

During the movement of the blank molds and neck rings from station C to station D, they are held in open position by their respective over-center-throw mechanisms above described. At station D means are provided for closing both the blank molds and neck rings, such means in the present instance comprising a means for closing the blank molds, the interlocking relation between the blank molds and neck rings being relied upon to close the latter.

The means for closing the blank molds and neck rings at station D is substantially similar to that for opening the blank molds at station C and is best shown in Figs. 3 and 4. This means comprises a pneumatic cylinder 76 suitably secured to the base 1 through brackets 77 and 78 as illustrated at the right in Fig. 3. The piston rod of the cylinder 76 carries a head 79 having upwardly projecting portions 80 similar to the portion 65 except that they are arranged to engage the radial inner portions of the rollers 61 and are designed at such an angle that they will be substantially concentric with the blank mold carrier at the closed position of the blank mold. In this case also the head 79 carries one or more guide rods 81 extending through a suitable hole or holes in the bracket 77 for preventing rotation of the head 79 about the axis of the piston rod associated with cylinder 76.

The piston in the cylinder 76 is moved inwardly of the blank mold turret by pneumatic pressure from the timer T supplied to the cylinder 76 through the pipe 82, this movement putting the parts in readiness for the closing of a blank mold and a neck ring. When it is desired to close a blank mold and a cooperating neck ring, pressure is exhausted through the pipe 82 by the timer T permitting the outward movement of the head 79 under the influence of the tension springs 83.

Locking means for molds

At various of the dwell stations both for the blank molds and the blow molds at which it is desired to perform some positive shaping opera-

tion upon the glass, it is necessary that there be some means more positive than that heretofore described for maintaining the molds closed, particularly against the force used in accomplishing the glass shaping operations. For this purpose I have illustrated mold locking means which are substantially of conventional form and are arranged to be operated by pneumatic cylinders in response to the timer T in a well known manner.

As shown for example at station A at the left in Figs. 1 and 2, there is a pneumatic cylinder 84 suitably mounted upon a bracket 85 which is in turn mounted upon the cover members 27 and 38 of the base 1. This cylinder has a piston rod 86 which is connected by a pair of links 87 with 15 clamping jaws 88 which are pivoted on a hollow sleeve 89 rigid with the bracket 85. The jaws 88 are adapted to engage portions either of the blank molds 46 themselves or the mold holders 47 carrying such molds. In the present instance 20 the mold holders are engaged by the clamping jaws 88. It will be understood that the same construction is used either identical or with variance only of proportion for the mold clamps at various other stations, there being mold clamps 25 as shown in Fig. 1 at stations A and B for the blank molds and stations G and H for the blow molds. The linkage is such that when the mold clamps are in a position as shown at station A in Fig. 2 clamping a blank mold shut, the links 30 87 are almost in a straight line, so as to form a toggle linkage to retain the molds shut against a material pressure. In an intermittent machine of the type here shown, all the mold clamping means may be connected in parallel so that there 35 need be but two valves in the timer T used for all the mold clamping means, one for moving the clamps from open to closed position and another for moving them from closed to open position. Pipe connections are shown between the cylinders 40 84 for the air passages to the timer at 90 and 91.

The charging funnel

At station A there is preferably provided a funnel for guiding charges of glass into a blank mold 45 through the open upper end thereof. It is to be understood, however, that if desired the upper ends of the blank molds may be made flaring and the molds made sufficiently longer than the desired length of the parisons so that the funnel 50 may be an integral part of the mold.

As shown, I provide a funnel 92 (Fig. 2) which is loosely received within a suitable opening in a bracket 93 carried by the stationary sleeve member 89. The bracket 93 may be adjusted 55 vertically upon the sleeve member 89 so that the lower edge of the funnel 92 will normally be slightly below the level of the upper surface of the blank molds. Thus the blank molds will move the funnel slightly upwardly on moving into station A, the loose fit of the funnel in the arm 93 permitting such movement. The funnel 92 will then rest upon the top of the blank mold being guided only to its position by the bracket 93.

The neck pin

While for some purposes, particularly in the construction of machines which are continuously rotated or in which the dwell is adapted to be 70 very short as compared to the time required for settling glass in the blank molds, it is necessary that the neck pin move with the molds, I have shown a construction in the accompanying drawings wherein the neck pin is mounted for use only 75

at station A and does not rotate with the blank mold carrier. The neck pin is not clearly illustrated in the accompanying drawings, but it will be understood that it is removably carried by the head 94 (Fig. 2) so as to permit the interchange of neck pins for making articles having different size and/or shape finishes. The head 94 is mounted upon the upper end of a piston rod 95 associated with a pneumatic cylinder 96, to the opposite ends of which pressure may be supplied from the timer T through pipes 97 and 98. The neck pin may thus be raised and lowered into and out of co-operative position in respect to the neck rings and blank molds while at station A by the application and exhaust of pressure to the cylinder 96.

The entire construction including the neck pin, the head 94 and cylinder 96 is preferably mounted for vertical adjustment with respect to the base 1, so as to provide for the making of articles of different heights. For this purpose, the cylinder 96 is carried by a threaded stud or shaft 99, which is received in a threaded opening 100 in a part of the base 1. The adjustment is made by threading the shaft 99 up or down in the opening 100 and then locking the parts in the desired position by means of the locking ring 101 which is threaded on the shaft 99 and is adapted to be tightened down against the upper surface of that portion of the base 1 in which the threaded opening 100 is formed.

Settle blowing means

While I contemplate that any means desired and/or any of those now in use in the commercial art may be employed for settling charges of glass in the blank molds 46 and forming finishes thereof in the neck rings and around the neck pin, I have shown in the present drawings a conventional type of settle blow head for this purpose. Referring to Fig. 2, there is illustrated a settle blow head 102 which is mounted for floating movement in a stationary head portion 103 mounted in the outer end of the arm 104 which is vertically adjustably secured to a vertical shaft 105. The connection between the head portion 102 and 103 is a loose floating one and includes a substantially semi-spherical contact surface therebetween to permit the head 102 seating itself properly upon the funnel 92, as shown, in order to obtain a tight joint when it is desired to apply settle blowing pressure to the interior of the blank mold. The member 102 is provided with a stud portion 106 rigid therewith and extending up into the chamber inside the head member 103 wherein it is formed with an enlargement so as to prevent any undue movement of the head member 102 with respect to the head member 103. The stud portion 106 is provided with suitable bores as illustrated for the passage of settle blowing pressure therethrough. Settle blowing pressure is conducted to the interior of the head member 103 through a suitable pipe 107 from the timer T, this pipe including a flexible portion (not shown) to permit of the necessary movement of the settle blow head.

Means are provided for moving the settle blow head 102 vertically and laterally between an operative position in cooperation with the funnel 92, as illustrated in Fig. 2, and an inoperative position above and laterally offset with respect to its operative position, so as to permit the dropping of a charge of glass vertically down through the funnel 92. This movement is accomplished by the use of a pneumatic cylinder 108 fixed to the

base 1 and having a piston 109 to which the shaft or rod 105 is connected as a piston rod. The cylinder 108 is supplied with actuating pressure through the pipes 110 and 111 from the timer T. Thus upon downward movement of the piston 109 in the cylinder 108, the head 102 will be moved downwardly to a position in cooperation with the funnel 92 as illustrated.

Means are also provided for moving the head laterally in response to its vertical movement, such means comprising an arm 112 secured to the shaft or piston rod 105 and carrying at its outer end a roller 113 working in a curved slot 114 formed in a sector shaped bracket 115 rigid with the cylinder 108. The configuration of the slot 114 is such that the lower end of the movement of the roller 113 and hence of the settle blow head 102 will be vertical, while the upper portion of this movement will be substantially helical, serving to rotate the head 102 about the vertical axis of the shaft 105 and thus move it laterally to an offset position with respect to the funnel 92 permitting the charging of the molds at station A by dropping charges of glass vertically through the funnel. This construction is conventional and is found in its equivalent form in the commercial "Hartford I. S." machine as illustrated and described in the Ingle Patent No. 1,911,119, above referred to.

The counterblow baffle

Station B of the machine shown in Figs. 1 to 7 is the counterblow station and at this station means are provided for counterblowing the charge of glass in the now upright mold, the charge having been supplied to the blank mold and settle blown therein at station A and the mold being then reverted to a neck-up position during its movement from station A to station B. The counterblowing is done in the machine of Figs. 1 to 7 solely at station B, so that the counterblow baffle and the counterblow head may be located at this station and not rotated with the blank mold carrier 8.

I have shown, therefore, a counterblow baffle 116 (Fig. 3) carried by the upper end of the piston rod 117 of a cylinder 118. Pressure is conducted to the upper and lower ends of this cylinder from the timer T in a manner not illustrated herein, but which will be easily understood. The cylinder 118 is vertically adjustably mounted upon a shaft 119 by means of a bracket 120 which may be integral with the cylinder 118 as shown. Thus the vertical adjustment compensates for molds of different heights. The shaft 119 is rigidly carried by a bracket 121 secured to the cover plate 27 of the base 1. The shaft 119 also carries the mold lock cylinder 84 used in conjunction with the mold at the counterblow station B as hereinbefore described.

The counterblow head

Means are provided according to my present invention to supply counterblowing pressure through the neck rings to expand the glass in the blank molds and complete the formation of the parison. In the present instance such means comprises a counterblow head generally indicated at 122, which is constructed and arranged in substantially the same manner as the settle blow head above described, that is it provides for free floating seating of the head against the neck ring. Counterblowing pressure is supplied to this head from the timer T through a pipe indicated at 123, which will include a flexible portion (not shown) to permit of the movement of the head

122. The head 122 is carried by the lower end of the piston rod 124 of a pneumatic cylinder 125 to the opposite ends of which pressure may be supplied from the timer T in the usual and well known manner, one of the pipes for this purpose being shown at 126. The cylinder 125 is carried by a bracket 127 from the stationary vertical shaft 119 above described. In order to provide for the vertical adjustment of the counterblow head to compensate for molds of different lengths, the bracket 127 is adjustably secured to the shaft 119.

The tongs—mounting and movement

- 15 As above described, there are a plurality of tongs, in this instance three, which are arranged for intermittent movement about a center laterally offset from the centers of the blank and blow mold carriers and having common transfer stations with each of these molds, the transfer station with the blank molds being station C and that with the blow molds being station F, and there being an intermediate station E at which the tongs support a parison for purpose of reheating, elongation, etc., in a manner to be described.
- 20 The tongs are carried by a vertical shaft 13 which is intermittently rotated as hereinabove described. The shaft 13 carries a pair of brackets 128 and 129 in which the vertical pivot shafts for the tongs are mounted. Inasmuch as the tongs are all similar, only one will be described.

The tongs comprise a pair of removable jaw members 130 secured to carrier members 131. These carrier members are mounted one on a hollow sleeve 132 and the other upon a concentric shaft 133 received within the sleeve 132, the sleeve being in turn journaled in the brackets 128 and 129. At their upper ends, that is above the bracket 128, the sleeve 132 and shaft 133 are respectively provided with crank arms 134 and 135, the hub of the lowermost of these arms bearing against the bracket member 128 so as to prevent vertical movement of the sleeve 132 with respect to the brackets. The crank arms or tongs carrier members 131 bear against each other and the uppermost thereof bears against the lower surface of the bracket member 129, thus preventing any vertical movement of the tongs with respect to the shaft 13. The tongs are adapted to close, as illustrated in Fig. 13, immediately beneath the neck ring 55.

Tongs opening and closing means—means for maintaining the tongs opened or closed

Means are provided tending to urge the tongs toward closed position. In the present instance such means taken the form of a tension spring 136 extending between suitable studs on the tongs carriers 131.

The linkages at the upper ends of the hollow shafts and sleeves 132—133 are best shown in Fig. 6 and each comprises the arms or cranks 134 and 135 above described. These arms or cranks of each tongs are pivoted at their outer ends to links 137 and 138 respectively which are pivoted together on a common pintle 139. When the parts are in the position as shown at the left in Fig. 6, the tongs are closed. The pintle 139 passes upwardly through a horizontally disposed cylindrical member 140 which is pinned thereto as indicated at 141 (Fig. 7). The member 140 is slidably received within a slotted tube 142 as shown in Figs. 2, 5 and 7, the pintle 139 passing upwardly and downwardly through the slots in the tube 142. These tubes 142 are secured to a suitable hub which in turn is secured to the tongs

carrier and shaft 13, so that they rotate with the shaft. In the closed position of the tongs, the corresponding cylindrical member 140 is at its outermost radial position in the tube 142, while in the open position of the tongs, seen at the right of the vertical shaft 13 in Fig. 2, the cylindrical member 140 is at its innermost radial position in the tube 142. At this innermost position in which the links 134, 135, 137 and 138 occupy the position seen at the upper right hand portion of Fig. 6, the links 137—138 have moved across the line of centers of their pivotal points with the links 134—135 so that there is in effect formed a toggle linkage preventing the closing of the tongs under the influence of the springs 136 at this time, these springs operating with the parts in this position to maintain the tongs open by tending to move the cylindrical member 140 radially inward rather than outward. Thus the tongs are resiliently held either in their open or closed position by the springs 136 and the linkage shown and hereinabove described.

During the movement of the tongs from station F to station C, they are maintained opened by the means hereinabove described. At station C, means are provided for closing the tongs to engage beneath a neck ring and grasp a parison to be transferred to a blow mold. This means comprises a pneumatic cylinder 143 secured to the upper structural member 11 (Fig. 2). The cylinder 143 has a piston 144 therein, the piston rod of which carries a spool 145 adapted to embrace the upwardly extending end of the pintles 139 of each of the tongs in succession and to move them from their innermost radial positions to their outermost radial positions, thus closing the tongs. For this purpose pressure may be supplied to the right hand end of the cylinder 143 as seen in Fig. 2 through the pipe 146 from the timer T, pressure being exhausted from the left hand end as seen in that figure through a vent opening 147. The piston 144 and the spool 145 are maintained in the position illustrated until the tongs have moved away from station C toward station E. During this movement of the tongs, the piston 144 is returned under the influence of the tension spring 148 extending between the upturned end of the piston rod which extends through the left hand end of the cylinder 143 and a suitable anchorage 149, this action being permitted by the exhausting of pressure through the pipe 146 by the timer T.

The tongs are thus closed at station C and are maintained closed during their movement to and through station E and to station F. At station F, means are provided for opening the tongs to release a parison to a blow mold once that mold has closed about the parison. For this purpose I have shown a cylinder 150, similar to the cylinder 143 and secured to the structural member 11. This cylinder has a piston 151, the piston rod of which carries a head 152 adapted to engage the radial outer sides of the pintles 139 to move these pintles radially inwardly of the axis of rotation of the tongs, that is to the position shown in Fig. 2 at the right of the shaft 13. For this purpose, pressure is supplied to the cylinder 150 through the pipe 153 from the timer T, pressure being exhausted from the opposite end of the cylinder through a suitable vent as illustrated. The piston 151 and the head 152 carried by the piston rod thereof may be returned at any desired time after the tongs have been opened and prior to the movement of the next tong into station F due to the fact that the

linkage above described will maintain the tongs open once they have been opened as above set forth. The return movement of the piston 151 to the right, as seen in Fig. 2, is accomplished by 5 the tension spring 154 extending between an upward extension of the head 152 and a suitable anchorage 155 fixed to the frame member 11.

Means for limiting elongation of parisons during transfer

10 For the purpose of limiting the elongation of parisons during transfer, it is sometimes desirable, although not in all cases absolutely necessary, to use a suitable bottom plate or elongation 15 stop. I have shown such an arrangement in the accompanying drawings and contemplate under certain circumstances using these bottom plates or stops, although my apparatus may under other circumstances and according to other methods be 20 utilized without these bottom plates or stops.

As shown in the accompanying drawings, however, there are a plurality of bottom plates or stops 156 arranged one below each of the tong 25 positions and pivoted on horizontal axes 157 to a suitable collar 158 vertically adjustably secured to the shaft 13 so as to rotate therewith. The vertical adjustment is provided so that articles of various lengths may be formed by the machine. These bottom plates or stops 156 are 30 adapted to slide over a suitably shaped substantially annular cam 159 secured to stationary parts of the machine and surrounding the shaft 13, the bottom plates 156 sliding over the upper surface of this cam. It is contemplated ordinarily that 35 the cam portion will be substantially horizontal from the station C to the station E and part way at least toward the station F. As illustrated in the accompanying drawings, the cam 159 terminates prior to the station F at 160 (Fig. 1) so 40 that the bottom plates fall after passing this point to a substantially vertical position from which they ride up an inclined surface of the cam in moving to the station C. This lowering of the bottom plates prior to the arrival of the tongs at 45 station F is required in order to permit the closing of the blow molds at this station. It is also desirable that the lowering be done relatively rapidly, as by a quick fall under the influence of gravity, in order that the glass may not sag too 50 far prior to being enclosed by the blow mold. The cam 159 will in the usual case also be vertically adjustable in order to provide for the making of bottles of different lengths, but this adjustment is not particularly illustrated in the accompanying 55 drawings.

I have shown in Figs. 19 and 20 a modified form of bottom plate or parison elongation limiting device, which may be desirable under certain circumstances. As shown in the drawings, the plate 60 156a is pivoted at 157 in the same manner as plate 156 above described. This plate has a depending portion which rides along the cam surface 159b as illustrated. The bottom of the parison is supported upon a bottom plate member 65 156b which is provided with a depending and preferably integral stem 156c extending loosely through a suitable aperture in the member 156a. Beneath the member 156a and surrounding the stem 156c there may be provided if desired a 70 light compression spring 156d extending between the under surface of the member 156a and a suitable stop on the stem 156c as a washer which may be secured in position, as by a cotter pin. The spring 156d, when used, tends to assist gravity in moving the bottom plate 156b downwardly 75

with respect to the member 156a. The vertical position of the bottom plate 156b is controlled by a second cam surface 159c, which is preferably formed in a plurality of segments integral with the member 159a on which are formed the cam surfaces 159b and 159c. These cam segments are spaced apart at each of the one or more intermediate dwell positions for the tongs in transferring parisons from blank molds to the blow molds, only one of these positions being illustrated in Fig. 20. At this position there is a movable cam segment 159d which is formed on the upper surface of a vertically movable head 159e.

I provide means for moving the cam segment 159d vertically to control the elongation of the 15 parison during the dwell at the intermediate station, such means in the present instance comprising a pneumatic cylinder 159f, on the piston rod on which the head 159e is mounted. Pressure may be conducted to and from the cylinder 159f 20 from and to the timer T through the pipes 159g and 159h, the latter entering the lower end of the cylinder as shown.

Provision is made for controlling the lowering movement of the piston within the cylinder 159f, 25 comprising a check valve 159i interposed in the pipe 159h and arranged to admit pressure freely into the lower end of the cylinder, but to prevent the reverse flow of pressure. In a by-pass associated with the pipe 159h and around the check 30 valve 159i is a needle valve 159j by which the exhaust is controlled, thus controlling the rate of lowering of the cam surface 159d.

Suitable means may be provided for limiting the movement of the piston in cylinder 159f in 35 both directions, such means comprising in the present case a nipple concentric with the piston rod and threaded in the upper head of the cylinder 159f, and a suitable set screw extending through the lower head thereof as shown.

The cylinder 159f may be suitably mounted upon the base of the machine and in view of the adjustments provided, may be utilized with different interchangeable cams 159a, such as are shown in Fig. 20. Suitable means may be provided for vertically adjusting cylinder 159f with respect to the base of the machine if desired, such means not being shown in the drawings as they may be of any conventional character. The last segment of the cam 159c terminates at 160a just 50 previous to the termination 160 of the cam surface 159b, so that the spring 156d will move the bottom plate 156b quickly downwardly out of contact with the bottom of the parison and in a vertical direction immediately prior to the swinging 55 down of the member 156a about the pivot 157 which occurs at the point 160 just prior to the arrival of the parison at the transfer station for the parisons from the tongs to the blow molds, this swinging down occurring as above set forth, 60 so as to provide for mechanical clearance for the parts of the machine.

The purpose of the vertical removal of the bottom plate 156b is to prevent the possibility of heel taps or other irregularities which may be caused 65 by the swinging down of the bottom plate, as shown in Figs. 1 and 2, about a horizontal pivot.

It will be noted that the contour of cam surface 159c is substantially horizontal in the early portion of the path of the parison (at the left, Fig. 20) when the parison is elongating but slowly and falls off more rapidly in the later portions when the parison is stretching or elongating more rapidly. Thus the bottom plate 156b may follow to some extent at least the normal elongation of 70 75 75

the parison and tend to limit this elongation beyond a certain point while permitting it to occur at a desired rate under control of the cam surface 159c.

5 *Puff blowing means*

At station E, I may in some instances desire to use puff blowing for expanding the parisons to some extent during their reheating and while 10 they are laterally unconfined. For this purpose, I have illustrated in Figs. 1 and 9 a bracket 161 extending laterally from a vertical shaft 162 which is supported by a bracket 163 from the base 1, the bracket 161 carrying at its inner end 15 a downwardly extending nozzle in vertical alignment with and slightly above the position of the neck of a parison supported in the tongs at station E. This nozzle is suitably connected to one of the valves of the timer T so that puff blowing 20 air may be supplied to the interior of the parison at station E under control of the timer. The bracket 161 is preferably adjustable as to its length and angular relation with respect to the shaft 162 and also is vertically adjustable with 25 respect to the shaft 162 so as to permit the vertical adjustment of the nozzle to the proper elevation for accommodating the machine to the manufacture of articles of various lengths.

This puff blowing is not a necessary step in my 30 process, although under certain circumstances it is useful and I prefer to provide it on a machine so that it may be used if and when desired.

35 *Blow molds and mounting therefor*

The blow mold carrier 9 is adapted to support a plurality of blow molds, either the same or different in number than the number of blank molds provided on the blank mold carrier 8. These molds may be formed in complementary portions 40 as is usual in the art and are shown at 164. The complementary portions of the blow molds 164 are carried by the usual holders 165 which are pivoted on pintles 166 secured in a table-like portion 167 of the carrier 9. The upper ends of the pintles 166 are shown as connected together for rigidity of construction by an annular ring 168. As illustrated, the blow molds are moved from the receiving station F at which the parisons are transferred thereto by the tongs, as above described, through the final blowing stations G and H to the takeout station I, there being four molds 50 in the machine illustrated. At stations G and H there is provided locking means as above described for retaining the blow mold halves closed.

55 *Opening and closing means for the blow molds and means for retaining them in open or closed position*

Each of the blow mold carriers is provided with 60 a threaded link 169 pivoted thereto on a vertical pivot 170, as best seen in Fig. 1 at station G. The links 169 pass loosely through suitable apertures in a cross head 171 which is guided for solely radial movement on a pair of rods 172, there 65 being a pair of lock nuts 173 on the inner ends of the links 169 inside the cross head 171 and spiral compression springs 174 being provided surrounding the links 169 and extending between shoulders on the links adjacent to their pivots 170 and the cross head 171. Thus upon radial inward movement of the cross head 171, the blow molds will be positively opened; while upon radial outward movement of the cross head, the molds 70 will be resiliently closed, the closing force being 75 determined by the compression of springs 174.

Each cross head carries a roller 175 on a vertical pivot by which movement is imparted thereto. The molds arrive at station F open and while at that station are closed about a parison by means hereinafter to be described. From station F 5 the blow molds remain closed while moving to and past stations G and H and up to station I, at which last station the blow molds are again opened to release the finished articles for the takeout operation.

I have provided a means for simultaneously opening one mold at the takeout station I and for closing another mold at the receiving or transfer station F, such means comprising an oscillatory cam 176 having in one sector a downwardly extending portion 177 arranged to engage the outer radial portion of the rollers 175 and at another sector a downwardly extending portion 178 arranged to engage the radial inward portion of the rollers 175. The ends of portions 177 and 20 178 are spaced apart so as to permit the rollers to pass therebetween.

Means are provided for oscillating the cam 176, such means comprising a pneumatic cylinder 179 suitably secured to the stationary column 6 above 25 the mold carrier as illustrated, this cylinder communicating at its opposite ends through pipes 180 and 181 with the timer T, so that pressure may be supplied thereto for moving the piston thereof in opposite directions at the desired times. The 30 piston rod 182 of the cylinder 179 has pivoted thereto at its outer end a link 183 connecting it with a stud on the oscillatory cam 176 eccentric of the column 6, so that upon movement of the piston rod 182 in the cylinder 179, the cam will be 35 oscillated as above described.

Surrounding the column 6 and immediately below the bearing portion for the oscillatory cam 176 is a stationary collar 184 the periphery of which for a material portion of its circumference 40 is at a constant distance from the axis of the column 6, this portion being in vertical alignment with the lower part of the rollers 175. The rollers 175 engage this constant radius portion 45 of the stationary cam member 184 shortly after they move away from station F and are in continuous engagement therewith until just before they arrive at station I. Thus the molds are maintained closed during this portion of their rotation under the influence of the compression springs 50 174. The sector from just before station I to just after station F is cut away permitting the molds to be open at each of these stations and to remain open in moving therebetween.

The movement of the cam 176 is so correlated 55 with the movements of the molds by the timer T that the cam will be in its farthest clockwise rotated position at the time each blow mold moves from station H to station I. When the mold arrives at station I and has stopped at that station, pressure is supplied through the pipe 181 60 and exhausted through the pipe 180 to rotate the cam 176 counterclockwise, as seen in Fig. 1, which results in opening the mold at station I and also 65 in closing the mold at station F. Just prior to the next movement of the molds the cam 176 is again oscillated, but this time in a clockwise direction as seen in Fig. 1, the mold at station I remaining open at that station and during its 70 movement to station F due to the friction of the parts. The mold at station F also remains closed about the parison by friction and inertia until this mold is moved to a point just beyond station F where the roller 175 thereof will engage the 75

outer periphery of the stationary cam member 184.

Blow mold bottoms and movements thereof

5 The blow mold bottoms are preferably made separate from the blow molds and are also preferably of the tilting type, being retained in their normal position by inter-engagement with the blow molds when the latter are closed. As illustrated, the blow mold bottoms 185 are interchangeably mounted upon the outer ends of arms 186 pivoted on horizontal axes 187 to the table portion 167 of the blow mold carrier. The interchangeable character of the bottoms permits bottoms of 15 different types to be used for the making of different types of articles.

During the time the molds are closed, the bottoms are held in position by engagement of the molds as above stated. However, the blow molds 20 are open at station I and not closed until after the molds have arrived at station F. During this period, therefore, means are provided for controlling the position of the bottoms, such means comprising a stationary cam member 188 suitably 25 secured to the base I and provided with a horizontal portion 189 at station I, so that the bottoms are not permitted to drop until after the mold has left this station, whereby the finished 30 bottles are supported in proper vertical position so that they may be grasped by hand, or by some suitable takeout device (not shown). In moving from station I toward station F, the mold bottoms are allowed to drop due to configuration of the 35 cam 188 as illustrated at 190 in Figs. 1 and 2. The cam 188 terminates just short of station F, so that at that station the bottoms are in their lowermost position, which is determined by the bottom raising means hereinafter to be described. 40 Thus in moving from station I toward station F the tipping of the bottom will permit any cullet or ware which has not been removed at station I to be tilted off the bottom by gravity.

It is necessary to provide means at station F 45 for raising the bottoms 185 beneath the bottoms of the parisons. For this purpose I prefer to employ a pneumatic cylinder 191 supported in an inclined position as shown upon the base I and adapted to receive pneumatic pressure through a 50 pipe 192 from the timer T, this pipe communicating with the lower end of the cylinder. The piston rod of the cylinder 191 is in alignment with the arms 186 when the molds are at station F, so that the admission of pressure through the pipe 55 192 from the timer will serve to move the bottoms to their operative horizontal position at which they may be enclosed by the closing of their associated blow molds. The return movement of the piston within the cylinder 191 is accomplished as 60 shown by a tension spring 193 extending between a stud on the piston rod and a suitable anchorage fixed with respect to the cylinder 191.

Final blow heads

65 While final blowing may take place at only one station or between stations under some circumstances and with suitable modifications, I have chosen to illustrate in the accompanying drawings 70 an arrangement in which final blowing takes place at stations G and H. Suitable mold locks are arranged at these stations for retaining the molds closed as hereinabove described.

Each of the final blow heads is similar to the 75 others so that only one will be described. Re-

ferring to Fig. 2, I have illustrated a final blow head at 194, this head being similar to the heads used for settle blowing and for counterblowing in that it permits the mold-contacting portion thereof to seat floatingly upon the blow mold under the influence of the seating pressure, the only difference being that the blow head is cupped at the lower portion, as illustrated, so as to surround the neck portion of an article which protrudes above the upper surface of the final blow molds. 10 Blowing pressure is supplied to the blow head 194 through the pipe 195 from the timer T, a portion of this pipe being formed flexible in a manner not shown to permit of movement of the blow head. The blow head 194 is mounted upon the lower end of a piston rod 196 projecting downwardly from a pneumatic cylinder 197 which is carried by a bracket 198 vertically adjustably secured to a vertical post or standard 199, whereby 15 to compensate for molds of different heights. The standard 199 is carried by a bracket 200 which in turn is supported by the base I through a bracket 201. Pneumatic pressure is conducted to the cylinder 197 to lower the blow head 194 20 through the pipe 202 from the timer T. Return movement of the blow head may be accomplished either by pneumatic pressure, or as shown, by the use of one or more tension springs 203 extending 25 between the blow head and suitable fixed 30 anchorages.

I preferably provide at the final blowing stations G and H, suitable means for preventing the force of the downward movement of the blow head from moving the molds downward and/or 35 out of proper alignment, such means comprising an adjustable anvil member formed as a screw threaded stud 204 threaded into a bracket 205 and locked in adjusted position by a nut 206, these anvils being suitably positioned at the blowing 40 stations beneath the blow molds so that any pressure exerted on the blow mold will be carried by the anvil rather than by the blow mold carrier.

Cycle of the machine, Figs. 1 to 7 and 9

Having now described the various constructions and the operating instrumentalities of the machine of Figs. 1 to 7, which is diagrammatically illustrated in Fig. 9, I will now describe the cycle 50 of operation of this machine.

Starting with one of the blank molds 46 at the position A beneath the funnel 92, the settle blow head 102 raised and swung to one side due to 55 pressure being supplied from the timer through the pipe 111 and exhausted through the pipe 110, and the neck pin in position in the neck mold due to pressure being supplied from the timer through the pipe 98 and exhausted through the pipe 97, 60 a charge of glass is supplied to the blank mold. The next operation is the lowering of the settle blow head 102, which is effected by the application of pressure to the cylinder 108 through the pipe 110 and exhausting of pressure through the pipe 65 111 from the timer. This lowers the settle blow head and swings it laterally to a position on the funnel 92, pressing that funnel against the blank mold and forming substantially air-tight joints between the settle head and funnel and between 70 the funnel and blank mold respectively. At about this same time, or possibly before the charge has been supplied in the mold, pressure is supplied to the mold locking cylinder 84 at station A through the pipe 90 and exhausted through the 75

5 pipe 91 to lock the mold. Pressure is then supplied through the pipe 107 and the passages in the settle blow head to settle blow the charge of glass about the neck pin. After this settle blowing operation has continued for the desired time, 10 pressure is cut off through the pipe 107 and the settle blow head 102 is raised and swung to one side due to the application of pressure through the pipe 111 and exhaust thereof through the pipe 110. At about this same time two other operations take place, first, the neck pin is withdrawn by the application of pressure to the cylinder 96 15 through the pipe 97 and exhaustion thereof through the pipe 98, and also the mold is unlocked by the application of pressure to the cylinder 84 at station A through the pipe 91 and exhaustion thereof through the pipe 90.

20 The blank mold in question is now moved from station A to station B, being inverted in the course of this movement due to the engagement of the gear 51 associated with the mold and the rack section 52, the mold arriving at station B in neck-up position. This intermittent rotation is 25 accomplished through the Geneva drive for the machine as a whole.

30 The next operation is the positioning of the counterblow baffle 116 by the admission of pressure to the lower end of cylinder 118 (Fig. 3) and the exhaustion thereof through the upper end of this cylinder. At about the same time the 35 mold lock cylinder 84 at station B is actuated to lock the mold at this station by the admission of pressure through the pipe 90 and exhaustion thereof through the pipe 91 of that cylinder. Also 40 at about the same time, the counterblow head 122 is positioned in cooperation with the mold by the admission of pressure to the cylinder 125 through the pipe 126. The parts are now in 45 position for the counterblowing, which is accomplished by the admission of pressure to the counterblow head through the pipe 123. After the counterblowing has continued for the desired 50 time, the reverse action takes place in connection with the cylinders 118 and 125, and the locking cylinder 84 at this station effecting the lowering of the counterblow baffle, the raising of the counterblow head and the unlocking of the mold at 55 station B.

50 The mold with the completed parison therein may now move from station B to station C, it being prevented from inverting during this movement by the sliding engagement between the flattened portion of the hub of the mold carrying head 49 and the stationary member 53 which engages such flattened portion. During this movement also the neck ring and blank mold are retained closed by the over center throw arrangements including the springs 69 and 62 respectively associated therewith.

60 At station C, the transfer station, the first operation is the opening of the blank mold leaving the neck ring closed to support the parison. This is accomplished by the admission of pressure to the cylinder 63 through the pipe 67. The next 65 operation is the closing of the tongs beneath the neck mold as shown in Fig. 13, which is accomplished by the admission of pressure to the pipe 146 of cylinder 143. The next operation at this 70 station is the opening of the neck ring leaving the parison suspended in the tongs, which is accomplished by the admission of pressure to the cylinder 72 through the pipe 73. The parison is now held in the position shown at the left 75 of the vertical shaft 13 in Fig. 2 supported in

the tongs and somewhat above the bottom plate or elongation limiting device 156 (see also Fig. 13). The parison is then brought by the next movement of the tables and tongs to station E as illustrated in Fig. 14. At this station, however, 5 puff blowing pressure may be applied if desired through the nozzle (not shown) from the timer, the nozzle being supported by the bracket 161 (Fig. 1). The glass is now elongating and the exterior surface thereof which has been 10 chilled by contact with the blank mold is softening due to the conduction of heat thereto from the interior portions of the glass.

15 The parison is then moved from station E to station F by the next movement of the tables and tongs, and during this movement the glass may stretch to reach the bottom plate or elongation limiting device 156, as illustrated in Fig. 15. Slightly before the parison reaches station F, the device 156 drops off the end 160 of the cam 159, 20 as shown in Fig. 1, so that the parison may now be enclosed within the blow mold and the bottom plate of that mold may be raised to position to support the lower end of the parison without mechanical interference of other parts. The 25 raising of this bottom plate is accomplished by the admission of pressure to the cylinder 191 through the pipe 192. The blow mold 184 is then closed about the parison at station F due to the admission of pressure to the cylinder 179, 30 through the pipe 181 and exhaustion thereof through pipe 180, rotating the oscillatory cam 176 counterclockwise, as seen in Fig. 1. The parts are now in the position shown in Fig. 16. The 35 next operation is the release of the parison to the blow mold by the tongs at station F, which is accomplished by the admission of pressure to the cylinder 150 through the pipe 153, moving the tongs to open position at station F, the tongs being retained in their open position by the 40 over-center-throw arrangement described.

45 The blow mold may then move successively to stations G and H, at each of which stations final blowing pressure may be supplied to the interior of the glass, first to blow it to final form and thereafter to retain it against the walls of the final blow mold for a time sufficient for the extraction of the heat necessary so that the 50 parison may be substantially completely set up upon removal from the machine. The seating of each final blow head is accomplished at each final blowing station by supplying pressure through the pipes 202 to the cylinders 197. Final blowing pressure is then applied through the 55 pipes 195 to the blow heads 194 and supplied through these blow heads to the interior of the glass. The parts are illustrated in Fig. 17 for this step of the process. It will be understood that at each of the stations G and H, there is a mold-locking cylinder 84 which is operated in the manner heretofore described for the mold lock cylinders of stations A and B.

60 The bottle has now been completed and the final blow mold, including this completed bottle, 65 is moved to station I, which is the takeout station. At this station the blow mold 164 is opened due to the admission of pressure to cylinder 179 through the pipe 181 and the exhaustion thereof through the pipe 180 thus rotating the cam 176 70 counterclockwise and opening the blow mold at station I. The completed bottle may then be removed either by hand or by some suitable automatic transfer device (not shown).

75 In moving from station I to station F, the 75

bottom plate is dropped to tilt off any article or cullet which may remain thereon.

In the form thus far described, station D for the blank mold is a cooling station and is not used except for the mechanical closing of the blank mold as heretofore described.

From the above it will be seen that I have provided a machine wherein a material part of the total time used for making the bottle is taken up with the glass outside any mold that is out of contact with any mold and out of registry therewith, by which is meant that the glass is out of any position in which either a blank or a blow mold might close around it. This term "out of registry" is to be construed broadly so that a position, for example, in vertical alignment with but above or below a mold, is to be termed "out of registry" therewith for the reason that the mold may be closed or used for some other purpose at a time that a glass parison or some partially formed article is in the "out of registry" position.

Novel parison formation in relation to machine cycle

The provision of a relatively long reheat period out of contact with any mold surface and out of registry with any of the molds lends itself particularly to the use of blank mold configurations having some portion greater in at least one dimension than the corresponding portion of the final article, so that the reheating time or a part thereof may be utilized for the stretching of the parison and the consequent attenuation of portions thereof to permit the reheated parisons to be enclosed within the blow mold. This method of operation and the configurations of the blank and blow molds for carrying it out are particularly illustrated in Figs. 11 to 17 and 18, wherein there is shown in Fig. 13 for example a form of parison larger in the neck portion, as illustrated at 207, than the outline for the final desired article which is superimposed on that figure in dotted lines for purposes of comparison. Passing along to Fig. 14, it will be seen that the parison has elongated to some extent, so that the neck portion is substantially the same size as the corresponding portion of the final desired article. Passing along a further step in the process (Fig. 15), it will be seen that the parison has elongated still further, so that it now rests upon the bottom plate 156 and the neck portion thereof is slightly smaller than the corresponding portion of the final desired article. This is further shown in Fig. 16 wherein somewhat more stretching or "running" of the parison and consequent attenuation has taken place and it is now enclosed within the blow mold. Upon expansion in the blow mold, the glass takes the form of the final desired article.

Fig. 18 shows a comparison of the upper portions of the blank and blow molds, the contour of the blank mold being shown in dotted lines at 208 and the contour of the blow mold being shown at 209 for purposes of comparison. The form of the molds shown in Fig. 18 is probably more accurate than that shown in Figs. 11 to 17 which has been exaggerated slightly to illustrate the principles involved.

The Figure 10 form of the invention

This form of the invention is substantially the same as to the construction of the blank and blow mold tables and the operations of the several parts as the form of the invention previously de-

scribed, the difference being that there are four tongs rather than three, the rate of rotation of the tongs being correspondingly changed, thus providing an extra reheating and/or puff blowing station. Thus in this form of my invention, there will be an overlapping time relationship between the reception of a charge in the blank mold, and the reheating of a parison formed from a charge previously supplied to the same blank mold. For example, one charge of glass may be supplied to and enclosed by a blank mold at station A' at the same time that a previous charge of glass formed into a charge in this same blank mold is at station F', reheating and being puff blown if desired, the charge of glass still earlier formed in the same blank mold being at station J', the take-out station, according to this cycle.

Figure 8 form of invention—tongs, mounting and operation

In Fig. 8 of the accompanying drawings, I have illustrated a modified form of my invention wherein the purpose is to provide for the use of the blank molds for a larger percentage of the total time, that is to provide a construction by which it is possible to have the blank molds in readiness to be supplied with a charge of glass at the first station after transfer, i. e., the station corresponding to station D of Figs. 1 and 9, the molds moving in the directions illustrated in Figs. 1 and 9. The tongs transfer means may be either of the Fig. 9 or Fig. 10 form, that is having either three or four arms for the transferring of parisons between blank molds and blow molds and in which there may be four or more blank molds and four or more blow molds on the respective blank and blow mold carriers. It will be understood, of course, that if a larger number of blank molds and blow molds be provided on the respective carriers, there will preferably be a correspondingly larger number of tongs provided, although the present number is deemed peculiarly advantageous in that it provides for a maximum use of the blank and blow molds.

In the Fig. 1 form of the invention it is impossible to feed the blank mold until the second station after transfer for the reason that it is impossible to start the inversion of the blank molds by the means shown at the transfer station, even though the molds could be closed at that station, due to the fact that there would be mechanical interference between the blank mold and the parison whether the molds be opened or closed should the inversion commence immediately. In order therefore to permit the inversion to start immediately on the mold starting its movement from station C toward station D, I have provided a novel form of tongs transfer in which the parisons are first lifted vertically from the parison mold while at the transfer station C and thereafter are moved about the axis of the tongs-carrying shaft 13 on a higher level, the parisons being subsequently lowered while at the blow mold transfer station F. It is contemplated of course that the lowering of the parisons might take place at any time once the parisons have cleared station C, but I have found the arrangement hereinafter to be described for Fig. 8 to be the most advantageous. The vertical lifting of the parison to a level completely above that of the blank mold permits the blank mold to be closed while at station C and the inversion of the blank molds to take place between stations C and D, so that the blank molds are in ready-

ness for the receipt of a next charge of glass at station D.

The blank molds and their operating means may be identical with the means hereinabove described for the Fig. 1 form of the invention, with the exception that the gear segment 52 and the invert preventing means 53 are positioned at an angle of substantially 90° counterclockwise with respect to the position in which these parts are shown in Fig. 1. This may be done by the same construction shown in Fig. 1, the parts being merely secured in the different relationship above described. Another change which is made in connection with the blank molds is that the mold opening means at station C be made positive for use both in opening and closing molds at this station. For this purpose the head 64' operated by the cylinder 63 is formed with a grooved trackway portion 210 for receiving the rollers 61. Also the mold closing cylinder 76 and its associated mechanism are omitted as it is unnecessary to provide another means for closing the mold, this operation taking place at station C. The charging funnel 92, the neck pin and its operating mechanism and the settle blow head and its operating mechanism will now be located at the station corresponding to station D of Figs. 1 and 9, so that a charge may be supplied to the mold and settle blown at this station. The counterblowing means described for station B in Figs. 1 and 9 will be either advanced one station to the station corresponding to station A or provided at both stations corresponding to station A and station B. Counterblowing may take place either wholly at the station corresponding to station A or partially at the stations corresponding to stations A and B, according to the desire of the operator, there being of course a mold locking cylinder 84 and associated mechanism at each of the stations corresponding to stations D, A and B. Alternatively, reversion from the neck-down to the neck-up position may take place between stations A and B instead of between stations D and A and counterblowing 45 may take place wholly at station A or partly at station A and partly at station B. It is believed unnecessary again to illustrate and describe all these parts as they are substantially identical with the construction illustrated in the Fig. 1 form of the invention and above described with the changes here noted.

The transfer means used in this form of the invention is somewhat different from that heretofore described. In the first place, the tongs 130' mounted upon holders or tongs carriers 131', instead of being mounted upon a coaxial sleeve and shaft, are mounted upon separate parallel shafts 211, the tongs carriers 131' being splined to these shafts respectively. The shafts 211, a pair of which are provided for each tongs, are suitably journaled in brackets 128' and 129' at their upper and lower ends. The means tending to close the tongs are shown as two springs 136' extending respectively between suitable detents as 212 on the bracket 128' and studs secured to cranks 134' and 135' respectively. The cranks 134' and 135' secured to the upper ends of the shafts 211 respectively are connected at their outer ends to links 137' and 138' respectively, as above described in connection with the description of Fig. 6, the parts being otherwise connected in exactly the same way as those heretofore described and being numbered correspondingly with a prime mark for differentiation. 75 These differences are necessary in order to permit

the vertical movement of the tongs. The over-center-throw arrangements are as nearly the same as those first described as possible in view of the differences in the parts and operations thereof as above described. The tongs actuating means are identical with those heretofore described.

Means are provided in connection with this construction for raising and lowering the tongs at the desired times, that is for raising the tongs 10 at station C, for maintaining them raised in their travel from station C to station F (referring to the stations as numbered in Figs. 1 and 9) and for lowering them at station F. For raising the tongs at station C, there is provided for each of 15 the tongs a yoke member 213 slidably received upon the rods 211 and embracing the portions of the tongs carrier members 131' which are splined on those rods. The yoke members 213 have extended portions 214 against the lower surface of 20 which the outer end of the lever 215 is adapted to impinge when the tongs are at station C. This lever is pivoted at 216 to a bracket 217 suitably secured to the stationary column 5 of the blank mold carrier. An intermediate portion of the lever 215 is pivoted at 218 to the lower end of the piston rod of a cylinder 219 which is pivoted at 220 to a bracket 221, which is likewise secured to the stationary column 5. Upon arriving at station C, the tongs are in their lower- 30 most position, so that once a blank mold 46 has been opened, as heretofore described, by the cylinder 63, the tongs may be closed by the cylinder 143 about a parison suspended from the neck ring 55. The neck ring is then opened, 35 leaving the parisons suspended from the tongs 130' at the lowermost position of the tongs. Pressure is then supplied through a connection (not shown) from the timer T to the lower end of the cylinder 219, which moves the piston 40 and piston rod of this cylinder upwardly to swing the lever 215 upwardly about its pivot 216. The right hand end of this lever as seen in Fig. 8 moves the yoke 213 and the tongs 130' embraced thereby upwardly to the level shown in Fig. 8 at 45 which the parison is completely above the level of the blank mold, so that the blank mold may then be closed by the cylinder 63 and may be moved from station C to station D and concomitantly inverted to bring it to station D in readiness to 50 receive a next charge of glass.

There is provided a semi-annular stationary plate 222 surrounding a portion of the rotatable shaft 13 between the transfer station for the parisons from the blank molds to the tongs and the transfer station of the reheated parisons from the tongs to the blow molds, this plate being secured to a bracket 223 which is in turn secured to the stationary column 6 of the blow mold carrier. This plate is cut away so as to permit the raising of the yoke member 213 to a level just above that of the plate, that is to a level such that the lower surface of the extension 214 is substantially even with or very slightly above the level of the top surface of the plate 222. Then upon the rotation of the tongs carrying shaft 13, the tongs will be maintained in their upper level position due to the extension 214 sliding over the upper surface of plate 222. At the time the tongs arrive at the transfer station for the blow molds, the lowering lever 224 will be at its uppermost position, that is so that the level of the left hand end thereof as seen in Fig. 8 will be substantially even with the upper surface of the plate 222, so that the extension 214 of the 70 75

yoke member 213 of the tongs will ride upon the outer end of this lever. Lever 224 is similar to lever 215 in that it is pivoted at 225 to bracket 226 secured to the stationary column 6. An intermediate portion on the lever 225 is pivoted as at 227 to the lower end of a piston rod 228 of a pneumatic cylinder 229, which is pivoted at 230 to a bracket 231 secured to the column 6. Thus when one of the yokes 213 of one of the tongs 10 rides upon the end of lever 224 pressure may be exhausted at the lower end of cylinder 229 and if desired supplied to the upper end of this cylinder for lowering the tongs and the parison held therein to the lower level position shown in Fig. 15 8, at which one of the blow molds 164 may close about the parison. The operation of the blow molds and the operations taking place in connection with these molds may be identical with that previously described.

20. Means are provided as shown in Fig. 8 for supporting the lower ends of the parisons and limiting their elongation, such means in the present instance comprising a cam 159' and suitable bottom plates 156', corresponding functionally 25 to the correspondingly numbered portions of Fig. 2. The cam 159' is supported slightly differently than the cam 159, in that it is carried by a stationary sleeve member 232 from the base 1, or more particularly from the top plate of the base 30 1. However, the parts are the full mechanical equivalents each of the other.

Alternative cycle for use with the Fig. 8 form of the invention

35. It is also contemplated as above generally referred to that the Fig. 8 form of the invention may be used with four blank molds, four tongs and four blow molds, substantially according to the arrangement diagrammatically illustrated in 40 Fig. 10 and with the charging station corresponding to station D' of that figure. Under these circumstances there will be what may be termed a "triple overlapping cycle", that is one charge of glass may have been supplied to a blank mold 45 at station D' and be enclosed thereby. The charge of glass previously supplied to this same mold will now be reheating in one of the tongs at station E' and at this position the parison will be out of contact with any body mold surface 50 and out of registry with either the blank or blow molds. The charge of glass next earlier supplied to the same blank mold will be enclosed within one of the blow molds at station I', the blow mold being closed and final blowing pressure may 55 be supplied thereto if desired, so that there will be at one time during each cycle of the machine as measured by the time interval between the supplying of successive charges of glass to the machine as a whole, three charges of glass all of 60 which were supplied to the same blank mold in the process of formation, the first, in a blank mold and possibly up to and including the point at which settle blowing pressure may be supplied thereto for forming a blank from the charge of 65 glass; the second, reheating out of contact and out of registry with any body mold surface, and the third, enclosed within a blow mold and being subjected to final blowing pressure therein.

70. While I have shown and described herein several embodiments of my invention and have suggested various cycles of operation for these different apparatus forms of my invention, it will be understood that various further modifications may be made both of apparatus and method all 75 within the spirit and scope of this invention. I

do not wish to be limited, therefore, except by the scope of the appended claims, which are to be construed as broadly as the state of the prior art permits.

I claim:

1. Apparatus for forming hollow glass articles, comprising two laterally spaced rotary carriers, blank molds on one of said carriers, means for forming parisons in said blank molds, final blow molds on the other of said carriers, at least three 10 tongs operating successively in the transferring of parisons from the blank molds to the blow molds and in a path such that at least one parison held in one of said tongs is always reheating out of contact and out of registry with said blank and 15 blow molds during the normal operation of the entire apparatus, a bottom plate associated with each of said tongs and movable therewith during the major portion at least of the transferring operation for determining the limit of elongation of a parison during such reheating, and means for blowing reheated and elongated parisons to final form in said final blow molds.

2. Apparatus for forming hollow glass articles, comprising a rotary carrier, means for rotating 25 said carrier intermittently, blank molds on said carrier and arranged to be brought by the intermittent rotation thereof to a plurality of dwell stations, a neck ring associated with each of said blank molds, said blank molds and said neck 30 rings being mounted for opening and closing movement on said carrier, means not partaking of the rotation of said carrier for independently opening said blank molds and said neck rings, and resilient means rotating with said carrier for 35 maintaining said blank molds and said neck rings in closed position after the blank molds and neck rings have been closed and for maintaining the blank molds and neck rings open after they have opened by the aforesaid opening means.

3. Apparatus for forming hollow glass articles, comprising a rotary carrier, means for rotating said carrier intermittently, blank molds on said carrier and arranged for opening and closing movement, said blank molds having at least one 45 roller associated therewith and arranged to be moved for opening and closing the blank molds in a direction having a substantial component radial of the carrier, and means not partaking of the rotation of said carrier and arranged adjacent 50 to one of the dwell positions of the blank molds for engaging said roller to move it from its position in which the associated blank mold is closed to a position in which such mold is opened, said means including a portion arranged for contact 55 with the roller which is formed substantially concentric of the carrier, whereby the blank mold may be opened and held open at the station at which it is opened by the opening means while at the same time rotation of the carrier for the 60 next rotative step is permitted prior to return movement of the blank mold opening means.

4. Apparatus for forming hollow glass articles, comprising two laterally spaced rotary carriers, four blank molds uniformly spaced about one of 65 said carriers, means for forming parisons in said blank molds, four final blow molds uniformly spaced about the other of said carriers, three tongs substantially uniformly spaced apart for rotation in an orbital path about a vertical axis 70 for transferring parisons from said blank molds to said blow molds, the tongs each supporting a parison for an angular distance of substantially 240° of its path, whereby at least one parison is always held out of contact and out of registry 75

with any of said blank and blow molds during the normal operation of the entire apparatus for reheating, and means for blowing the reheated parisons to final form in said blow molds.

5. Apparatus for forming hollow glass articles, comprising rotary carrying means, blank molds and blow molds carried thereby, means for forming parisons in said blank molds, at least four tongs operating successively in the transferring 10 of parisons from the blank molds to the blow molds and in a path such that at least two parisons held in two of said tongs are always reheating out of contact and out of registry with said blank molds and said blow molds during the normal 15 operation of the entire apparatus, means for blowing the reheated parisons to final form in said blow molds, and timing means so constructed and arranged that during each cycle of the machine as measured by the time between the supplying 20 of successive charges to said blank molds there will be at least two charges of glass simultaneously in the process of formation as follows: one having been supplied to one of said blank molds and being enclosed thereby, and another, 25 which was earlier formed into a parison in the same blank mold, reheating in one of said tongs as aforesaid.

6. Apparatus for forming hollow glass articles, comprising two laterally spaced rotary carriers, blank molds on one of said carriers, means for forming parisons in said blank molds, final blow molds on the other of said carriers, a plurality of tongs operating successively in transferring parisons from the blank molds to the blow molds and 35 in a path such that at least one parison held in one of said tongs is always reheating out of contact and out of registry with said blank and blow molds during the normal operation of the entire apparatus, means for blowing reheated parisons 40 to final form in said blow molds, and means for timing the operations of all the aforesaid means so that during each cycle of the machine as measured by the time interval between the supplying of successive charges of glass to said blank molds, there will be at least two charges of glass simultaneously in the process of formation as follows: one having been supplied to one of said blank molds and being enclosed thereby and at least one other, which was supplied to the same blank mold 45 and formed into a parison therein, reheating in one of said tongs as aforesaid.

7. Apparatus for forming hollow glass articles, comprising two laterally spaced rotary carriers, means for rotating said carriers, four blank molds 55 on one of said carriers and arranged to be brought by the rotation of the blank mold carrier successively to a charging and settle blowing station, a counterblowing station, a transferring station and a cooling station, means at said settle blowing station for settle blowing charges of glass in the blank molds and forming neck finishes thereon, means operative during the movement of the blank molds from the settle blowing station to the counterblowing station for reverting the molds to 60 present them at the counterblowing station neck uppermost, means at the counterblowing station for counterblowing the settled charges of glass in the molds and thereby forming such charges into parisons, four final blow molds uniformly spaced 65 around the other of said carriers and adapted to be brought by the intermittent rotation of the blow mold carrier successively to a transferring station, two final blowing stations and a takeout station, a third rotary carrier having four tongs 70 uniformly spaced therearound, means for rotat-

ing said third carrier intermittently and in timed relation to the first two named carriers to move the tongs successively to the transferring station of the blank mold carrier, two reheating stations in which parisons held in the tongs are out of contact and out of registry with either the blank or blow molds and the transferring station of the blow mold carrier in the order named, means at least at one of said reheating stations for puff blowing parisons held in the tongs, means at the final blowing stations for blowing parisons into final blow molds to final form therein, and means for timing the operations of all the aforesaid means, whereby during each cycle of the machine, as measured by the time interval between the supplying of successive charges of glass to the blank molds, there will be at least two charges of glass in the process of formation into completed articles as follows: one having been supplied to one of a blank mold and being enclosed thereby and another which was formed into a parison in the same blank mold reheating in one of said tongs at one of said reheating stations for the tongs as aforesaid.

8. Apparatus for forming hollow glass articles, comprising rotary carrying means, blank molds and blow molds carried thereby, means for forming parisons in said blank molds, at least three tongs operating successively in the transferring 30 of parisons from the blank molds to the blow molds and in a path such that at least one parison held in said tongs is always reheating out of contact and out of registry with either the blank or blow molds during the normal operation of the apparatus, means for opening and closing the blank molds, means for moving the tongs to transfer parisons as aforesaid, said tongs moving means and the blank mold operating means being so constructed and arranged that each blank mold is in readiness for the receipt of a next charge of glass after it has passed from the point at which a parison is removed therefrom by one of said tongs a distance substantially equal to the angular spacing between the blank molds on the blank mold carrier, means for blowing reheated parisons to final form in said final blow molds, and timing means for the several parts of the machine constructed and arranged to operate the machine in a cycle in which one charge of glass has been supplied to a blank mold and is enclosed 40 thereby at the same time that a charge of glass which was previously supplied to the same blank mold and formed into a parison therein is being supported by one of said tongs out of contact and out of registry with either said blank or blow 45 molds for reheating.

9. Apparatus for forming hollow glass articles, comprising two laterally spaced rotary carriers, means for rotating said carriers intermittently, blank molds on one of said carriers, means cooperating with said blank molds for forming parisons therein, final blow molds on the other of said carriers, at least three tongs operating successively in the transferring of parisons from the blank molds to the blow molds and in a path 60 such that there is at least one dwell position for the tongs intermediate their transfer stations with the blank and blow molds respectively, this intermediate dwell position for the tongs being one in which a parison held therein will be out of contact and out of registry with either the blank or blow molds for reheating, means for intermittently moving said tongs in said path as aforesaid, means for opening and closing the tongs, means for opening and closing said blank 65

molds, the above named means being so constructed and arranged that each blank mold is closed in readiness for the receipt of a next charge of glass at the first station for such molds after 5 the transfer station at which parisons are removed therefrom by the tongs, means for blowing parisons to final form in the blow molds, and means for timing the apparatus so that one charge of glass will have been supplied to one of 10 the blank molds and be enclosed thereby at the same time that another charge of glass, which was formed into a parison in the same blank mold, is being supported for reheating in one of the tongs at the intermediate position thereof 15 as aforesaid.

10. Apparatus for forming hollow glass articles, comprising rotary carrying means, blank molds and blow molds carried thereby, means for forming parisons in said blank molds, means for 20 blowing parisons to final form with said final blow molds, transfer means comprising at least three tongs for transferring parisons from the blank molds to the blow molds in a path such that at least one parison held in one of said tongs 25 is always reheating out of contact and out of registry with said blank molds and blow molds during the operation of the entire apparatus, and means for so timing the operations of all the aforesaid means that at one time during each 30 cycle of the machine, measured by the time interval between the supplying of successive charges of glass to the blank molds, at least three charges of glass will be simultaneously in the process of formation into completed articles 35 as follows: one having been supplied to one of the blank molds and being enclosed therein, a second, which was formed into a parison in the same blank mold, reheating in one of the tongs as aforesaid, and a third, which was still earlier 40 formed into a parison in the same blank mold, being enclosed within one of said blow molds.

11. The method of forming hollow glass articles in a rotary type machine, which comprises supplying charges of molten glass to blank molds, 45 moving said blank molds in a substantially circular path, forming the charges into parisons in such blank molds, moving blow molds in a substantially circular path, transferring the parisons thus formed while supported in tongs to the 50 blow molds through a path substantially all of which is out of registry with the paths of the blank and blow molds and such that parisons will be held out of contact and out of registry with either the blank or blow molds for a period of 55 time during which each blank mold will move a distance at least equal to the angular space between such molds on the blank mold carrier, blowing the parisons to final form in the blow molds, and so timing the aforesaid operations 60 in the normal operation of the machine that during each cycle of the machine as measured by the time interval between the supplying of successive charges of glass to successively charged blank molds, at least two charges of glass will be simultaneously in the process of formation into completed articles, one having been supplied to a blank mold and being enclosed thereby and another which was supplied to and formed into a parison in the same blank mold reheating in one 65 of the tongs out of registry and out of contact with either the blank or blow molds.

12. The method of forming hollow glass articles in a two-table rotary type machine, which comprises supplying charges of molten glass to 70 blank molds, moving said blank molds in a sub-

stantially circular path, forming the charges into parisons in said blank molds, moving blow molds in a substantially circular path, transferring the parisons thus formed while supported in tongs to the blow molds through a path of substantial length, which path is substantially completely out of registry with the paths of the blank and blow molds except for the points thereon at which transfer of parisons to and from the tongs are made, blowing the parisons to final 10 form in the blow molds, and so timing the aforesaid operations in the normal operation of the machine that during each cycle of the machine, as measured by the time interval between the supplying of successive charges of glass to 15 successively charged blank molds, at least three charges of glass will be simultaneously in the process of formation into completed articles as follows: one having been supplied to a blank mold and being enclosed thereby; a second, which 20 was formed into a parison in the same blank mold, being supported by one of the tongs at a portion of the path thereof out of contact and out of registry with either the blank or blow molds; and a third, which was still earlier formed into 25 a parison in the same blank mold, being enclosed within one of the blow molds.

13. Apparatus for forming hollow glass articles, comprising two laterally spaced rotary carriers, means for rotating said carriers intermittently, 30 four invertible blank molds on one of said carriers equally spaced therearound, means for forming parisons in said blank molds and for presenting the parisons for transfer in neck-up position, four final blow molds on the other of 35 said carriers, means for blowing parisons to final form in said final blow molds, means for transferring parisons from said blank molds to said blow molds comprising a third rotary carrier arranged for intermittent rotation in synchronized 40 time relation with the blank and blow mold carriers, four tongs on said third carrier, means for opening and closing said tongs, means for holding said tongs in either opened or closed position, means for raising and lowering said tongs, 45 means at the common transfer station of the blank molds and tongs for opening and thereafter closing said blank molds, means for inverting the blank molds to a neck-down position during their travel from the transfer station to 50 the next succeeding dwell station, whereby said blank molds may be in readiness for the receipt of their next charges of glass as the next dwell station after such transfer station, and means 55 for timing the operations of all the aforesaid means.

14. The method of forming hollow glass articles, which comprises forming parisons having finished neck portions in a blank mold to a shape and size 60 shorter than the articles to be formed and having at least one transverse dimension intermediate the ends of such parisons greater than the corresponding dimension of the article to be formed, suspending the parisons thus formed by their 65 finished neck portions for reheating out of contact and out of registry with any body mold surface for a material length of time to provide for the gravity elongation of the parisons and consequent attenuation thereof sufficient to permit their receipt within a final blow mold, enclosing the parisons thus reheated, elongated and attenuated within a final blow mold, and blowing the parisons to final form therein.

15. The method of forming hollow glass ar- 75

- ticles, which comprises forming parisons having finished neck portions in a blank mold to a shape and size shorter than the articles to be formed and having at least one transverse dimension intermediate the ends of such parisons greater than the corresponding dimension of the article to be formed, suspending the parisons thus formed by their finished neck portions for reheating out of contact and out of registry with any body mold 10 surface for a material length of time to provide for the gravity elongation of the parisons and consequent attenuation thereof sufficient to permit their receipt within a final blow mold, enclosing the parisons thus reheated, elongated and attenuated within a final blow mold, blowing the 15 parisons to final form therein, and so timing the performance of the above-recited steps of the method that at least two charges of glass will be simultaneously in the process of formation into 20 finished articles as follows: one having been supplied to the blank mold and being enclosed thereby, and a second, which was formed into a parison in the same blank mold, reheating as aforesaid.
16. The method of forming hollow glass articles, which comprises forming parisons having finished neck portions in a blank mold to a shape and size shorter than the articles to be formed and having at least one transverse dimension intermediate the ends of such parisons greater than the corresponding dimension of the articles to be formed, suspending the parisons thus formed by their finished neck portions for reheating out of contact and out of registry with any body mold 30 surface for a material length of time to provide for the gravity elongation of the parisons and consequent attenuation thereof sufficient to permit their receipt within a final blow mold, enclosing the parisons thus reheated, elongated and attenuated within a final blow mold, blowing the parisons to final form therein, and so timing the performance of the above-recited steps of the method that at least three charges of glass will be simultaneously in the process of formation into 35 finished articles as follows: one having been supplied to the blank mold and being enclosed thereby; a second, which was formed into a parison in the same blank mold, reheating as aforesaid; and a third, which was still earlier formed into a parison in the same blank mold and later reheated as aforesaid, being enclosed within the final blow mold.
17. The method of forming hollow glass articles in a rotary type machine, which comprises supplying charges of molten glass to blank molds, moving said blank molds in a substantially circular path, forming the charges in such blank molds into parisons of a shape and size shorter than the articles to be formed and having at least one transverse dimension intermediate the ends thereof greater than the corresponding dimension of the articles to be formed, moving blow molds in a substantially circular path, transferring the 40 parisons thus formed while supported in tongs to the blow molds through a path substantially all of which is out of registry with the paths of the blank and blow molds and such that the parisons will be held out of contact and out of registry with either the blank or blow molds for a period of time during which each blank mold will move a distance at least equal to the angular space between such molds in their path, whereby to provide for the gravity elongation of the parisons and consequent attenuation of parts thereof suffi- 45
- cient to permit the parisons to be received within the final blow molds, blowing the parisons to final form in the blow molds, and so timing the aforesaid operations in the normal operation of the machine that during each cycle of the machine, as measured by the time interval between the supplying of successive charges of glass to successively charged blank molds, at least two charges of glass will be simultaneously in the process of formation into completed articles as follows: one 50 having been supplied to a blank mold and being enclosed thereby and another, which was supplied to and formed into a parison in the same blank mold, reheating in one of the tongs as aforesaid.
18. The method of forming hollow glass articles in a rotary type machine, which comprises supplying charges of molten glass to blank molds, moving said blank molds in a substantially circular path, forming the charges in the blank molds 55 into parisons of a shape and size shorter than the articles to be formed and having at least one transverse dimension intermediate the ends of such parisons greater than the corresponding dimension of the articles to be formed, moving blow molds in a substantially circular path, transferring the parisons thus formed while supported in tongs to the blow molds through a path of substantial length, which path is substantially out of registry with the paths of the blank and blow molds except for the points thereon at which the transfer of parisons to and from the tongs take place, and during such transfer providing for the reheating of the parisons and the gravity elongation and consequent attenuation of parts thereof 60 sufficient to permit their receipt within the final blow molds, blowing the parisons to final form in the blow molds, and so timing the aforesaid operations in the normal operation of the machine that during each cycle of the machine, as measured by the time interval between the supplying of successive charges of glass to successively charged blank molds, at least three charges of glass will be simultaneously in the process of formation into completed articles as follows: one 65 having been supplied to a blank mold and being enclosed thereby; a second, which was formed into a parison in the same blank mold being supported from one of the tongs at a portion of the path thereof at which the parison is out of contact and out of registry with either the blank or blow molds, and a third, which was still earlier formed into a parison in the same blank mold, being enclosed within one of the blow molds.
19. Apparatus for forming hollow glass articles, comprising rotary carrying means, blank molds and blow molds carried thereby, means for forming parisons in said blank molds, tongs operating to transfer the parisons from the blank 70 molds to the blow molds through a predetermined path, means including a vertically movable bottom support for controlling the elongation of parisons held in said tongs at least during a part of the transfer from the blank molds to the blow molds, means for predetermining and varying the vertical position of said bottom support while it is in cooperative relation with a parison held in said tongs, and means for blowing reheated and elongated parisons to final form in said final blow molds.
20. Apparatus for forming hollow glass articles, comprising rotary carrying means, blank molds and blow molds carried thereby, means for forming parisons in said blank molds, tongs operating 75 to transfer parisons from the blank molds to

the blow molds by movement through a pre-determined path, a vertically movable bottom support moving with said tongs during a portion at least of the travel thereof in moving a 5 parison from a blank mold to a blow mold, means for controlling and varying the vertical position of the bottom support throughout its cooperative travel with the tongs, and means for blowing reheated and elongated parisons to 10 final form in said final blow molds.

21. Apparatus for forming hollow glass articles, comprising rotary carrying means, means for rotating said carrying means intermittently, blank molds and blow molds carried by said 15 carrying means, means for forming parisons in said blank molds, at least three tongs operating successively in transferring parisons from said blank molds to said blow molds, means for moving said tongs intermittently in synchronized 20 time relation with the movements of said carrying means and in a manner such that there is at least one dwell station for the tongs intermediate the dwell station at which parisons are 25 transferred from the blank molds to the tongs and the station at which parisons are transferred from the tongs to the blow molds, vertically movable bottom supports associated with each of said tongs and arranged for movement therewith during a major portion at least of their path 30 of travel in transferring parisons from the blank molds to the blow molds and to and through said intermediate dwell station for the tongs, means for predetermining and varying the vertical position of the bottom supports to control the 35 elongation of parisons held in the tongs both during movement of the tongs and at said intermediate dwell station, and means for blowing

reheated and elongated parisons to final form in said final blow molds.

22. Apparatus for forming hollow glass articles, comprising rotary carrying means, means for rotating said carrying means intermittently, blank molds and blow molds carried by said carrying means, means for forming parisons in said blank molds, at least three tongs operating successively in transferring parisons from said blank molds to said blow molds, means for moving said tongs intermittently in synchronized 10 time relation with the movements of said carrying means and in a manner such that there is at least one dwell station for the tongs intermediate the dwell station at which parisons are 15 transferred from the blank molds to the tongs and the station at which parisons are transferred from the tongs to the blow molds, vertically movable bottom supports associated with each of said tongs and arranged for movement 20 therewith during a major portion at least of their path of travel in transferring parisons from the blank molds to the blow molds and to and through said intermediate dwell station for the tongs, stationary cam segments for predetermining 25 and varying the vertical position of said bottom supports during movement thereof with the tongs, a vertically movable cam segment for controlling the vertical movement of said bottom support while the associated tongs are at 30 said intermediate dwell station thereof, means for imparting a predetermined vertical movement to said vertically movable cam segment during a dwell of the tongs, and means for blowing reheated and elongated parisons to final 35 form in said final blow molds.

GEORGE E. HOWARD.
